[57] CLAIM

The ornamental design for a tire, as shown and described.

DESCRIPTION

FIG. 1 is a perspective view of a tire embodying a first embodiment of my design, it being understood that the tread pattern is repeated throughout the circumference of the tire, the opposite side being substantially the same as that shown;

FIG. 2 is a front elevational view of said first embodiment;

FIG. 3 is a side elevational view of said first embodiment;

FIG. 4 is a perspective view of a tire embodying a second embodiment of my design, it being understood that the tread pattern is repeated throughout the circumference of the tire, the opposite side being substantially the same as that shown;

FIG. 5 is a front elevational view of said second embodiment;

FIG. 6 is a side elevational view of said second embodiment.

FIG. 1

FIG. 2

FIG. 3

FIG. 4

FIG. 5

FIG. 6
